UNITED STATES PATENT OFFICE.

RICHARD JAHN, OF FRANKFORT-ON-THE-ODER, GERMANY.

COVER OR LID FOR USE IN CONNECTION WITH AIR-PROOF PRESERVE-BOXES AND THE LIKE.

1,091,577.

Specification of Letters Patent.

Patented Mar. 31, 1914.

Application filed November 30, 1912. Serial No. 734,308.

To all whom it may concern:

Be it known that I, RICHARD JAHN, a subject of the King of Prussia, German Emperor, and resident of Frankfort-on-the-5 Oder, in the Kingdom of Prussia, German Empire, have invented a new and useful Cover or Lid for Use in Connection with Air-Proof Preserve-Boxes and the like, of which the following is a specification.

10 This invention relates in general to preserving boxes and similar vessels of the kind, in which it is possible to produce in the box or vessel, between its cover or lid and the article of food to be preserved, a partial 15 vacuum, the cover or lid being pressed upon an india-rubber ring or the like located between said cover and said vessel by the greater pressure of the atmosphere. In particular my invention relates to such a 20 cover or lid, *i. e.* to a special construction of the same, and my improvement consists in providing the cover or lid with a downwardly projection having a plurality of 25 grooves adapted to hold, chiefly by adhesion, spirit or another combustible liquor by means of which the air in the box or vessel above the article of food to be preserved and below the cover or lid may be heated so as to expand. The cover or lid has an opening 30 or aperture through which the excess of the volume of air may escape, and as soon as the spirit or other combustible liquor in the said grooves has been consumed, that is to say, when the expansion of the 35 air by the heating has attained the possible maximum, that opening or aperture is closed by a stopper or disk or the like of india-rubber or another suitable material, and as the heated air inclosed in the upper part of 40 the box or vessel cools down, its volume lessens and a partial vacuum arises, whereupon the cover or lid is pressed upon the india-rubber or other packing by the greater 45 pressure of atmosphere.

50 In order to make my invention more clear, I refer to the accompanying drawing in which similar letters refer to similar parts, and in which:

Figure 1, is a vertical section through a 55 preserve glass provided with a cover constructed according to my invention. Fig. 2 is a vertical section through another form of such cover. Fig. 3 is a part of a cover having another shape of the downwardly extending projection, and Fig. 4 is a similar

representation showing also another configuration of the projection.

The cover or lid *a*, Fig. 1, has a downwardly extending projection *b*, which in the form shown resembles a knob. This projection or knob has a number or plurality of horizontal grooves *c* which are intended to hold, by adhesion, the spirit or other combustible liquor, as stated previously. The cover or lid has also an opening *d* which 60 may be closed by a stopper *e*. When the grooves *c*, that is to say, practically the whole of the surface of the projection *b*, are covered with spirit, and this liquor has been ignited, the cover is placed upon the 65 vessel, *i. e.* upon the packing *g* of the same, and as soon as the combustible liquor is consumed, the stopper *e* is introduced into the opening *d* of the cover, after which the 70 remaining heated and expanded air in the vessel *f* will cool down and the cover will be pressed, and held fast, upon the vessel so as to prevent any contact of the article of food 75 therein contained and the outer air.

In the form of construction shown in Fig. 80 2, the horizontal grooves *c* of Fig. 1 are replaced by vertical ones, *c*¹, and in the form of construction represented in Fig. 3, I have made use of inclined grooves *c*², where as in the fourth form represented in Fig. 4 a combination of horizontal and vertical grooves 85 is employed. The projection or knob *b* of this form of execution has an elongation *b*¹ containing a comparatively deep groove *b*² which is also intended to receive a certain 90 quantity of spirit, for the purpose as described.

As to Fig. 2, there is the other difference, that there is an india-rubber disk *e*¹ instead of the plug *e*, and the aperture *d* is replaced by a recess *d*¹ having a hole *d*². These 95 features do not belong to the essential contents of the invention.

I wish it to be understood, that I do not 100 limit myself to exactly such projections and such grooves as represented in the drawing. These are all merely examples, which allow of many deviations in various respects without departing from the invention.

Having now described my invention, what 105 I desire to secure by a patent of the United States is:

1. A cover for use in connection with preserve vessels, comprising a plate, a downwardly extending rim forming part of said 110

plate and being adapted to fit over the neck of a preserve vessel; and a grooved projection extending downwardly from the middle of the said plate slightly beyond said rim, for the purpose as described.

2. A cover for use in connection with preserve vessels, comprising a horizontal plate, a rim extending at right angles to said plate from the periphery of same and being adapted to fit over the neck of a preserve vessel; a grooved projection extending down-

wardly from the middle of the said plate slightly beyond said rim, the lower part of said projection forming a circular recess adapted to receive and hold liquid fuel, substantially and for the purpose as described. 15

In testimony whereof I affix my signature in presence of two witnesses.

RICHARD JAHN.

Witnesses:

WALTHER LUKELAND,
HENRY HASPER.
